United States Patent Office.

WARREN HILL, OF SPRINGFIELD, MASSACHUSETTS.

Letters Patent No. 79,470, dated June 30, 1868; antedated May 5, 1868.

IMPROVEMENT IN TICKET-PUNCHES.

The Schedule referred to in these Letters Patent and making part of the same.

TO ALL WHOM IT MAY CONCERN:

Be it known that I, WARREN HILL, of Springfield, in the county of Hampden, and Commonwealth of Massachusetts, have invented a new and improved Ticket-Punch; and I do hereby declare that the following is a full, clear, and exact description thereof, reference being had to the annexed drawings, making a part of this specification, and to the letters of reference marked thereon, in which—

Figure 1 is a side elevation of said ticket-punch.

Figure 2 is a longitudinal vertical section, showing details of construction.

Figure 3 is a plan view of the die-spindle, and

Figure 4 is an elevation of the same.

My invention relates to that class of punches used by railroad-conductors and others, for forming or "punching" holes in tickets and papers, for the purpose of indicating that the ticket or paper has been cancelled, inspected, or has passed through certain hands; and it consists in a certain construction and operation of the punching-spindle or male die and its appurtenant parts.

The construction of my invention is as follows:

The general form and appearance of the two levers A and B are the same as in other punches of the same class, the handle-portion being curved to accommodate the hand of the operator, and a slot being formed in the lever B for the insertion of the ticket or paper.

The levers A and B are pivoted together at the end, the semicircular ear upon A entering the space between the cheeks *a* upon the other lever, and are secured by the screw *b*, which passes through both.

The projecting part *b'* of the lever A comes in contact with the part *g'* upon B, and prevents the levers from opening beyond a certain distance.

The form of the spindle or male die C is shown in figs. 2, 3, and 4.

This spindle is made of steel, and has a projection, *i*, at the top, which is rounded and inclined, as shown. The form of the die is cylindrical, and the lower end is shown as circular, but may be made of any conformation which fancy or business purposes may require.

A cylindrical opening, *j*, in the lever B, above the ticket-slot, serves as a guide for the die-spindle; and the female die is formed in the upper face of that part of B below the ticket-slot *h*, which female die is to be made of the same outline as the end of the die-spindle C, and fitting the same closely.

As the cutting effect is produced by the shearing action of the meeting edges of the male and female dies, it is necessary that such edges should be sharply cut.

If the levers should be made of brass or other soft metal, it will be necessary to insert a steel die-plate to serve as the female die; but if made of iron or a harder metal, the female die may be formed in the lever itself, as shown.

The opening *g*, beneath the female die, is made slightly conical, to facilitate the passage of the portions of the ticket or paper which are cut away by the dies.

In the lever A is formed a recess or seat for the end, *i*, of the die-spindle, and it is evident that as the end of the lever A is pressed toward B, the die-spindle will also be moved through the guide *j* until it enters the female die and produces a cutting action.

To raise the die-spindle, when the levers are opened again, I attach the projecting plate *e* rigidly to the side of the spindle, which has a circular portion and a neck, which enters the spindle, and is fastened securely therein; or I may form the die-spindle C and its projection *e* in one piece, or from one piece of metal.

Beneath this circular plate *e*, I form a recess, *f'*, in B, and insert a spiral spring, *f*, the upper end of which bears against the plate, and tends to raise the die-spindle.

The spindle, therefore, is not directly attached to either lever, but after being inserted in its place, cannot be removed without removing the screw *b* and detaching the levers.

It will be seen that the spindle, being independent of the lever A, will always move in the line of the guide

j, without binding against its sides, which it could not do if pivoted to the lever *A*; and also, that a more efficient cutting or shearing effect is thereby obtained.

At the outer end of each lever, I form the cylindrical projection *d*, which is turned down at *m*, to form a stem, which enters the spiral spring *k*, fig. 1.

The spring *k*, if applied so that the ends embrace the stems *m m* upon the levers, and press open the ends of the levers, will remain in place, and serve the purpose of a finger-loop as well as an opening-spring.

The stems *m m* are made of a length sufficient to allow the levers to approach so far as to bring the die-spindle into contact with the female die, and produce the proper cutting effect, and no farther, and thus serve as stops, thereby making the operation of cutting more easy to the hand, and less injurious to the dies, than if no stops were applied.

Instead of forming the projection *e* upon the spindle, and placing the spiral spring beneath it, and at one side of the spindle, as shown, a collar might be formed upon the upper part of the spindle, and the spring applied around the spindle, and bearing against the collar; but I prefer the construction shown in the drawings, as it enables me to place the spindle nearer the fulcrum of the levers.

I am aware that a device has been used as a ticket-punch, as shown in Letters Patent granted to William J. Phelps, and dated September 17, 1867; but my device differs from that very materially in its construction, inasmuch as said Phelps's device has a spindle which is pivoted to one lever by a small pivot, which is liable to breakage, and the levers, when forced apart, withdraw the die-spindle from the female die by means of said pivot, whereas in my device no pivot is used, the spiral spring, which is placed under the projection of the die-spindle, forcing the said spindle out of the female die, while, at the same time, the said spring may be of sufficient strength to force the levers apart.

By this construction I am enabled to place the die-spindle nearer the fulcrum, and also cause the lever *A* to bear wholly upon the extreme end of the die-spindle *C*, and thus increase the power of the punch to perforate the thicker board or paper tickets.

Having described my invention, what I claim as new therein, and desire to secure by Letters Patent, is, as an improvement upon the invention of the said William J. Phelps—

The construction and arrangement of the spindle *C*, projection *e*, and spiral spring *f*, in combination with the lever *A*, recessed at *c'*, and the slotted lever *B*, substantially as described.

In testimony whereof, I have hereunto set my hand, this twenty-sixth day of December, A. D. 1867.

WARREN HILL.
